(57) **CLAIM**

The ornamental design for a dual sided grater, as shown and described.

DESCRIPTION

FIG. 1 is a perspective view of a novel design for a dual sided grater;

FIG. 2 is a frontal plan view of the dual sided grater of FIG. 1; FIG. 3 is a dual sided grater viewed at 90 degrees from the view of FIG. 2;

FIG. 4 is a rear view of the dual sided grater of FIG. 1;

FIG. 5 is a top plan view of the dual sided grater of FIG. 1; and,

FIG. 6 is a bottom plan view of the dual sided grater of FIG. 1.

The broken lines are for illustrative purposes only and form no part of the claimed design.
